(57) **CLAIM**

The ornamental design for a catheter tunneler adapter, as shown and described.

DESCRIPTION

FIG. 1 is an isometric view of a first embodiment of catheter tunneler adapter according to the present invention.

FIG. 2 is a front view of the catheter tunneler adapter shown in FIG. 1.

FIG. 3 is a top view of the catheter tunneler adapter shown in FIG. 1.

FIG. 4 is a bottom view of the catheter tunneler adapter shown in FIG. 1.

FIG. 5 is a distal end view of the catheter tunneler adapter shown in FIG. 1.

FIG. 6 is a proximal end view of the catheter tunneler adapter shown in FIG. 1

FIG. 7 is an isometric view of a second embodiment of catheter tunneler adapter according to the present invention.

FIG. 8 is a front view of the catheter tunneler adapter shown in FIG. 7.

FIG. 9 is a top view of the catheter tunneler adapter shown in FIG. 7.

FIG. 10 is a bottom view of the catheter tunneler adapter shown in FIG. 7.

FIG. 11 is a distal end view of the catheter tunneler adapter shown in FIG. 7; and,

FIG. 12 is a proximal end view of the catheter tunneler adapter shown in FIG. 7.
